UNITED STATES PATENT OFFICE.

WILLIAM G. HARLAN, OF CENTRALIA, WASHINGTON.

RAILWAY-SWITCH.

1,132,717.

Specification of Letters Patent. Patented Mar. 23, 1915.

Application filed May 20, 1913. Serial No. 768,864.

To all whom it may concern:

Be it known that I, WILLIAM G. HARLAN, a citizen of the United States, residing at Centralia, in the county of Lewis and State of Washington, have invented certain new and useful Improvements in Railway Switches, of which the following is a specification.

This invention relates to new and useful improvements in railway switches and has for its primary object to provide means whereby the switch may be thrown from the train while in motion. In this way, the need of a switchman at different points to throw the switch is obviated and the cost of maintenance of the road materially reduced.

In the accompanying drawings: Figure 1 is a plan view of my improved railway switch. Fig. 2 is a similar view with some of the parts shown in horizontal section. Fig. 3 is a longitudinal section. Figs. 4 and 5 are transverse sections taken on line 4—4 and 5—5, respectively. Fig. 6 is a transverse section taken on line 6—6 of Fig. 1 with the front of a locomotive shown in dotted lines and the switch thrower in full lines. Fig. 7 is a detail fragmentary view showing the adjustable connection between the wire cables and the cross chains for connecting the cables with the trip levers, the parts shown on an enlarged scale. Fig. 8 is a diagrammatic view showing how the switch thrower may be applied to each end of the cars of the train, and Fig. 9 is a diagrammatic plan view showing an arrangement whereby the switch thrower carried by the locomotive may be operated from the cab.

Referring to the drawings for a more particular description of the invention and which drawings are for illustrative purposes only and are therefore not drawn to scale, 1 indicates the cross ties, 2 the rails of the main track and 3 the rails of the switch or siding.

In carrying out my invention, I provide the main track at the switch or siding with a pair of vertically disposed trip levers 3¹ and 4 which are pivoted on the bearing shaft 5 extending through the longitudinal strips 6 which extend across the top of an adjacent pair of cross ties. The trip levers 3¹ and 4 are provided in front of the switch (assuming that the train is traveling in the direction indicated by the arrows) and a pair of corresponding trip levers 7 and 8

also mounted in a similar manner in front of the switch, assuming that the train is traveling in the opposite direction. I also provide a pair of trip levers 9 and 10 which are pivoted to the cross rod 11 extending across and secured to the top of an adjacent pair of cross ties in the siding. The switch tongues which are indicated by the reference numeral 13 are pivoted, as at 14, to the cross tie 15 in the usual manner and are connected together at their free ends by the transverse locking bar 16. One of the tongues is connected by the link 17 with the vertical post 18 which is mounted to partially turn on the cross tie 18¹ and is provided with a horizontal base portion 19 secured to the outer ends of the longitudinally disposed locking keys 20, which are arranged longitudinally of the track with their inner ends sliding through corresponding openings in the guide or keeper bar 21, secured on top of the cross tie 22 and adapted to engage notches *a* formed in the edge of the locking bar 16. The vertical post is further provided with the upwardly projecting portion which extends through and above a corresponding opening 23 in the top of the guide frame 24 secured to the cross ties by the downwardly extending legs 25. The trip levers are connected with the ends of the portion 19 by the wire cables 26, 27, 28, 29, 30 and 31, respectively, which are about $\frac{1}{8}$ inch in diameter and work over the horizontal rollers 32 and between the vertical guide rollers 33, mounted on the brackets 34 suitably secured to the cross ties in the proper position. The ends of the wire cables 26 to 31 inclusive are connected with the trip levers by the cross chains 35 to 40, respectively.

It will be observed that the chain 35 has one end connected to the trip lever 3 below its pivot and its opposite end connected with trip lever 4 above its pivot. This same system is carried out with reference to the three sets of trip levers and chains, opposite ends of one chain of each set being connected with the trip levers at points above and below their pivots and opposite ends of the other chain of each set being connected in like manner, with the inner portions of each pair or set of chains crossing or intersecting as shown in Fig. 1 of the drawings. It will be understood that suitable slots are provided in the switch tongues for the passage of the wire cables and the switch may be

thrown while the train is in motion by operating the trip levers.

To operate the trip levers, I provide what I term a switch thrower comprising a pair of vertically adjustable plunger bars 41 connected by the cross link 42 with the front end of the rock shaft 42¹ which extends into the cab of the engine and is provided with the handle 42². The plunger bars 41 work through corresponding guide slots formed in the cross pieces 43 of a suitable bearing frame. The switch thrower may be attached to the front of a locomotive in any suitable manner and a switch thrower will be attached to each end of the cars and especially when applied to freight trains. In attaching the switch thrower to the respective cars, the operating lever for the plunger bars can be placed at the corner where the lever is situated which withdraws the pin in the car coupler. Under these circumstances, in backing the train on a switch, the brakeman pulls the lever which lowers one of the plunger bars in position to throw the switch without the brakeman getting off the train. When the lever 42² is in horizontal position, both plunger bars are raised sufficiently to clear the trip levers without throwing the switch. An ordinary switch light 45 is connected with the switch stand by the rod 46 or other equivalent means so that the engineer can tell whether the switch is open or closed.

It is obvious that by means of the trip levers, the switch may be closed or opened while the train is in motion. For example, say the train is traveling in the direction indicated by the arrows in Fig. 2, with the switch closed, as shown, and it is desired that the switch be opened so that the train will pass from the main track to the switch or siding. In this case, the plunger bar 41 at the left hand side of the locomotive is lowered which causes the wire cable 31 to turn the vertical shaft and open the switch. Turn buckles 46 or some other form of adjustable connections are employed for connecting the ends of the cross chains with the wire cables, whereby the tension of the cables may be regulated.

In Fig. 9 of the drawings, I have shown how the switch thrower may be carried at the front of the locomotive and a rock shaft and hand lever provided whereby the switch thrower may be operated from the cab of the engine.

Fig. 8 is a diagrammatic illustration of how the switch thrower may be attached to each end of the cars of the train. In this case, the lever 42² is pivoted to the upright bearing bar 42³ which is secured to the cross pieces of the bearing frame. It is to be understood, however, that I do not limit myself to any particular style or form of switch thrower, nor any particular manner of se-

curing same to the locomotive or cars of the train, but reserve the right to use any style or form of switch thrower and secure it in position as best adapted to meet the requirements.

Attention is called to the fact that when the switch is closed, one of the locking keys 20 engages the adjacent notch in the locking bar 15 and holds the switch in either open or closed position, as the case may be, until thrown by one of the trip levers in which case the locking key is disengaged and the other locking key engaged with the other notch in the bar to hold the switch in its new position until again operated. In this way, I entirely avoid accidents by what is known as "open switches."

From the foregoing description taken in connection with the drawings, it is thought that the construction, operation and many advantages of this invention will be readily understood without requiring a more extended explanation.

Various changes in the form, proportions and minor details of construction will be resorted to without departing from the principles or sacrificing any of the advantages of this invention as defined in the appended claims.

Having described my invention what I claim as new, is:—

1. A railway switch of the character specified comprising pairs of pivoted trip levers, a vertical shaft connected with one of the tongues of the switch, means including wire cables for connecting the trip levers with said shaft and locking means comprising a pair of longitudinally disposed locking keys and a transverse locking bar connected with the free ends of the switch tongues and provided with notches alternately engageable with the locking keys whereby the switch may be securely locked in thrown position.

2. A railway switch comprising pairs of vertically disposed pivoted trip levers, a vertical shaft connected with one of the tongues of the switch and mounted to turn on the track and means comprising wire cables and cross chains for connecting the trip levers with the vertical shaft, whereby the switch may be thrown from one position to the other by throwing one of the trip levers, horizontal and vertical guide rollers for the wire cables and adjustable connections between the wire cables and cross chains.

3. A railway switch comprising pairs of vertically disposed pivoted trip levers, a vertical shaft connected with one of the tongues of the switch and mounted to turn on the track, means comprising wire cables and cross chains for connecting the trip levers with the switch stand, whereby the switch may be thrown from one position to the other by throwing one of the trip levers,

horizontal and vertical guide rollers for the wire cables, adjustable connections between the wire cables and cross chains, and locking means comprising a pair of longitudinally disposed locking keys and a transverse locking bar connected with the free ends of the switch tongues and provided with notches alternately engageable with the lock-

ing keys, whereby the switch may be securely locked in thrown position.

In testimony whereof I affix my signature in presence of two witnesses.

WILLIAM G. HARLAN.
